[57] CLAIM

The ornamental design for a video cassette rewinder, as shown and described.

DESCRIPTION

FIG. 1 is a top, front and right side isometric view of a video cassette rewinder showing my new design;

FIG. 2 is a top plan view thereof;

FIG. 3 is a right side elevational view thereof, the left side being a mirror image of the right side shown;

FIG. 4 is a bottom plan view thereof;

FIG. 5 is a front elevational view thereof;

FIG. 6 is a rear elevational view thereof; and,

FIG. 7 is a top, front and right side isometric view thereof, shown with the top in an open position.
